CLAIM

I claim the ornamental design for the machine cabinet, as shown and described.

DESCRIPTION

FIG. 1 is a front perspective view of a first embodiment of a machine cabinet showing my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and

FIG. 7 is a bottom plan thereof.

In FIGS. 1-7, the surfaces having angled lines on them depict transparent surfaces; the remaining surfaces in these figures are solid.

FIG. 8 is a front perspective view of an alternative embodiment of a machine cabinet showing my new design;

FIG. 9 is a front elevational view thereof;

FIG. 10 is a left side elevational view thereof;

FIG. 11 is a right side elevational view thereof;

FIG. 12 is a rear elevational view thereof;

FIG. 13 is a top plan view thereof; and,

FIG. 14 is a bottom plan thereof.

In FIGS. 8-14, the surfaces having hatching on them depict screened surfaces; the remaining surfaces in these figures are solid.

The broken lines in the drawings depict unclaimed environmental subject matter.
